UNITED STATES PATENT OFFICE.

CHARLES G. WHITAKER, OF PHILADELPHIA, PENNSYLVANIA.

DESIGN FOR A BICYCLE HANDLE-BAR.

SPECIFICATION forming part of Design No. 31,364, dated August 8, 1899.

Application filed September 24, 1895. Serial No. 563,556. Term of patent 7 years.

To all whom it may concern:

Be it known that I, CHARLES G. WHITAKER, a citizen of the United States, residing in Philadelphia, Pennsylvania, have invented a certain new and useful Design for a Bicycle-Handle, of which the following is a specification.

My design for the handle-bar of a bicycle is fully illustrated in the accompanying drawing, in which is shown a perspective view of the handle-bar.

The main feature of the design is the oblong center piece, square in cross-section, situated midway between the handles of the bar and having its angles disposed in horizontal and perpendicular planes, with a circular stud projecting from the upper angle of the center piece.

A is the polygonal center piece, that shown being four-sided, and a^2 is the stud projecting from one angle of the same. Extending from each end of the center piece are curved bars a^1 , round in cross-section and having handles a' at their outer ends.

I claim—

The design for the handle-bar of a bicycle, substantially as described and as shown in the accompanying drawing.

In testimony whereof I have signed my name to this specification in the presence of 30 two subscribing witnesses.

CHARLES G. WHITAKER.
